REFRIGERATOR PULLOUT SHELF

Herbert D. Squire, Galesburg, Ill., assignor to Midwest Manufacturing Corporation, Galesburg, Ill., a corporation of Illinois

Application July 30, 1956, Serial No. 601,051

14 Claims. (Cl. 312—332)

This invention relates generally to a pull-out shelf construction, and is directed particularly to a pull-out shelf construction for use on a refrigerator or the like.

In the ordinary, everyday use of refrigerators it is highly desirable that one or more of the food-supporting shelves be of the pull-out type, so that the food at the back of the shelf may be more conveniently reached.

The present invention is directed to a novel pull-out shelf arrangement which is particularly advantageous for use on domestic refrigerators.

Accordingly, it is an object of the present invention to provide a novel and improved pull-out shelf arrangement particularly adapted for use on a refrigerator.

It is also an object of this invention to provide a novel pull-out shelf arrangement having novel provision for readily mounting the shelf on its support structure.

Other objects and advantages of the present invention will be apparent from the following description of a preferred embodiment thereof, which is described in detail hereinafter as applied to a domestic refrigerator and is illustrated in the accompanying drawing.

In the drawing:

Figure 1 is a top view of the present pull-out shelf arrangement, looking down on the shelf from inside the refrigerator;

Figure 2 is a section taken along the line 2—2 in Fig. 1;

Figure 3 is a section taken along the line 3—3 in Fig. 1;

Figure 4 is a section taken along the line 4—4 in Fig. 1; and

Figure 5 is a section taken along the line 5—5 in Fig. 1.

Referring first to Fig. 1, the refrigerator is provided with the usual inner liner, consisting of a back wall 10 and spaced side walls 11, 12 and open at the front 13 of the refrigerator, which normally is closed by a door (not shown). A pair of sockets 14 and 15 extend through the back wall 10 adjacent the side walls 11 and 12, respectively. At their inner ends these sockets terminate in transverse annular flanges 16 and 17, respectively, which engage the inner face 10a of the back wall 10. The sockets are rigidly supported by the back wall 10 and define axial recesses which are open at the flanges 16 and 17, respectively, to receive tightly the back ends of rigid elongated guide rails 18 and 19, respectively, which are circular in cross-section. These guide rails extend in spaced, parallel relation to the respective adjacent side walls 11 and 12 horizontally toward the front of the refrigerator. At their front ends the guide rails 18, 19 are rigidly supported by brackets 20 and 21, respectively, which are mounted on the inner faces of the side walls 11 and 12, respectively, near the front of the refrigerator.

The refrigerator shelf itself is of generally conventional construction, including front, back and side rails 22, 23, 24 and 25, a plurality of spaced rod-like bars 26 extending between the front and back rails, and a rod-like middle cross bar 27 extending from one side to the

2

other. The side rail 24 of the shelf is slidably supported on a flat, horizontal upwardly facing guide surface 28 on bracket 20, as best seen in Fig. 4. This bracket has an inwardly protruding lip 29 which overlies the side rail 24 to prevent substantial upward displacement of the shelf thereat.

The other bracket 21 on the other side wall 12 of the refrigerator is of identical construction and supports the side rail 25 of the shelf in the same way.

Attached to the shelf back rail 23 is a horizontal rail 51 (Fig. 1) which at either end has a downwardly and forwardly offset horizontal extension arm 51a spaced directly below the shelf back rail 23 (Figs. 2 and 3). At the left side of the shelf this extension arm 51a carries a slide 31, which is formed with a downwardly facing, transverse, horizontal channel 70 which receives the extension arm 51a. In this manner, slide 31 is physically supported by the extension arm 51a and is slideable therealong laterally of the shelf, toward and away from guide rail 18.

At its connection to the side rail 24 the back rail 23 of the shelf is snugly received in an upwardly facing channel 30 formed in slide 31 (Figs. 2 and 3). Slide 31 is formed with a longitudinal channel 32, opening through the outer side of the slide, which slidably receives the guide rail 18, so that the slide 31 is slideable along this guide rail from front to back, or vice versa, in the refrigerator. The channel 32 in the slide 31 is elongated transversely, so as to permit adjustment or movement of the slide toward and away from the guide rail 18.

The slide 31 has an integral rearwardly projecting protrusion 33 for engagement with the flange 16 on socket 14 to limit the movement of slide 31 toward the back of the refrigerator.

In accordance with the present invention, the slide 31 has a manually releasable spring connection with the shelf to allow it to move in and out on the shelf and facilitate assembly thereof with the guide rail and to facilitate mounting the attached slide and shelf on the guide rail. To this end there is provided a flexible resilient spring, indicated generally at 34 in Fig. 2, which has a curved bent over end 35 received in a pocket 36 in slide 31 which is open at the top of the slide. This end portion 35 of the spring is joined to a substantially flat segment 37 which extends up at an angle across an upwardly facing transverse channel 38 in the slide 31 extending away from the upper end of pocket 36 therein to the inner side edge 39 of the slide. Segment 37 projects up between two adjacent bars 26 on the shelf. At its outer end the spring segment 37 terminates in a generally inverted U-shaped segment 40 which bears tightly against the outer side edge of one of these bars, as best seen in Fig. 2. The opposite lower end of the inverted U-shaped spring segment 40 is bent out to extend horizontally at 41 and then downwardly at an angle in a looped free end segment 42.

Slide 31 also is formed with a finger-engaging protrusion 43 which projects forward at the inner side edge 39 of the slide and presents a tapered outer side face 43a.

At the right side of the shelf, the downwardly offset right end extension arm 51a of rail 51 supports a slide 50 which is similar to the just-described slide 31 and has an identical releasable spring connection to the shelf. Slide 50 is provided for the purpose of mounting the shelf slidably on guide rail 19.

Just behind the support brackets 20 and 21 the respective guide rails 18 and 19 carry rearwardly extending sleeves 60 and 61, respectively, which are positioned to be engaged by the front ends of the respective slides 31 and 50 to limit the forward movement of the slides and the attached shelf.

In the assembly of the shelf onto the refrigerator, the

slides 31 and 50 initially are positioned inwardly along the respective extension arms 51a at the back of the shelf. Slide 31 may be so positioned by placing the forefinger of the left hand against the tapered inner face 43a of protrusion 43 on this slide and the thumb against the free end 42 of spring 34, and causing the thumb to depress the free end 42 of the spring, pulling the spring segment 40 down past the shelf bar 26 against which it abuts normally. This releases the spring connection between the shelf and slide 31, so that the slide may be moved to the right in Figs. 1 and 2, along the shelf back rail 23 and the extension arm 51a. The same adjustment can be made of the other slide 50 at the right side of the shelf.

With the slides so positioned, the shelf is pushed back into the refrigerator, with the shelf side rail 24 resting on the support surface 28 on bracket 20 and the other shelf side rail 25 similarly supported by bracket 21. Slide 31 is then pushed outward (to the left in Figs. 1 and 2) until the guide rail 18 is disposed within the outwardly facing channel 32 on this slide. The free end 42 of spring 34 is then manipulated to snap the upper end 40 of this spring in place, bearing against the outer side of one of the bars 26 on the shelf. Slide 50 and its spring are similarly manipulated to allow the slide to move in and out on guide rail 19 and to hold it in proper position relative to the shelf.

It will be noted that slide 31 is assisted in its insertion between the arms 51a and 51 by reason of the fact that the end 51b of the arm 51a is bent downward as best shown in Fig. 2.

In the use of the foregoing pull-out shelf construction, the shelf may be pulled out to its extended position simply by grasping the front rail 22 of the shelf and pulling it forward. The slides 31 and 50 slide along their respective guide rails 18 and 19 until they abut against the stop sleeves 60 and 61. At this time, the shelf is supported on both guides and is connected thereto as shown in Fig. 2, so that the shelf and slides move forward as a unit.

The shelf may be retracted simply by pushing it back into the refrigerator, with the guides 31 and 50 and the shelf moving as a unit at this time, also.

From the foregoing it will be apparent that the illustrated embodiment of the present pull-out shelf arrangement is of rugged and simplified construction which is adapted for low-cost manufacture and assembly, and which at the same time is capable of the effective and advantageous mode of operation just described.

It is to be understood that, while there has been described in detail herein and illustrated in the accompanying drawing a specific preferred embodiment of this invention, various modifications, omissions and refinements which depart from the structural details of the disclosed embodiment may be adopted without departing from the spirit and scope of the present invention.

I claim:

1. In a pull-out shelf construction, the combination of a slide, a shelf supported on the slide to move as a unit therewith, said slide being mounted to be adjustably positioned laterally of the shelf, and spring means carried by the slide and engaging the shelf to retain the slide at a predetermined lateral position with respect to the shelf, said spring means being manually operable to disengage from the shelf for the adjustment of the slide laterally of the shelf.

2. In combination on a refrigerator, a pair of guide rails rigidly supported within the refrigerator at opposite sides thereof and extending from front to back, a pair of slides supported individually by said guide rails for sliding movement therealong, each of said slides being formed with a channel which has an open end at its outer side larger than the corresponding guide rail and which receives the corresponding guide rail, a shelf, and means releasably connecting said shelf to said slides to move as a unit therewith, each of said slides being adjustable later-

ally of the shelf toward and away from the guide rail on which it is mounted.

3. In combination on a refrigerator, a pair of guide rails rigidly supported at the back of the refrigerator and extending horizontally at opposite sides of the refrigerator from back to front, a pair of support brackets mounted on the sides of the refrigerator adjacent the front of the refrigerator and supporting the front ends of said guide rails, each of said brackets presenting an upwardly facing support surface above the corresponding guide rail, a pair of slides mounted respectively on said guide rails for sliding movement therealong, each slide having a channel therein which receives the corresponding guide rail, each channel having an open end at the outer side of the slide which is larger than the respective guide rail for initially receiving said guide rail when the slide is mounted thereon, a shelf, and means releasably connecting the shelf to said slides to move as a unit therewith, said shelf overlying said support surfaces on the brackets for sliding movement thereacross, at least one of said slides being adjustable laterally on the shelf toward and away from the guide rail on which it is mounted.

4. The combination of claim 3, wherein each of said guide rails carries a sleeve extending back from the respective support bracket and positioned to be engaged by the slide on that guide rail to limit the forward movement of that slide.

5. The combination of claim 3, wherein each of said support brackets has an inwardly extending protrusion which overlies the shelf to limit upward displacement of the shelf therat.

6. The combination of claim 3, wherein each of said slides has a channel which is open at the outer side of the slide and which receives the corresponding guide rail therat.

7. In combination on a refrigerator, a pair of guide rails rigidly supported at the back of the refrigerator and extending horizontally at opposite sides of the refrigerator from back to front, a pair of support brackets mounted respectively on the sides of the refrigerator adjacent the front of the refrigerator and rigidly supporting the front ends of said guide rails, each of said brackets presenting an upwardly facing support surface above the guide rail supported thereby, a pair of slides mounted respectively on said guide rails for sliding movement therealong, each slide having a channel therein which receives the respective guide rail, each channel having an open end at the outer side of the slide which is larger than the respective guide rail for the mounting of the slide on the guide rail, a shelf having opposite side rails and a back rail, each of said slides having an upwardly facing channel which receives the back rail of the shelf, each of said side rails of the shelf resting on said support surface on the corresponding support bracket, and each of said slides being mounted for adjustment laterally of the shelf toward and away from the respective guide rails.

8. In combination on a refrigerator, a pair of guide rails rigidly supported at the back of the refrigerator and extending horizontally at opposite sides of the refrigerator from back to front, a pair of support brackets mounted respectively on the sides of the refrigerator adjacent the front of the refrigerator and rigidly supporting the front ends of said guide rails, each of said brackets presenting an upwardly facing support surface above the guide rail supported thereby, a pair of slides mounted respectively on said guide rails for sliding movement therealong, a shelf having opposite side rails, a back rail and a plurality of spaced rods extending forward from said back rail between the side rails, said shelf carrying a pair of horizontal arms disposed below said back rail at either side of the shelf which support the slides individually and which extend toward said guide rails, each of said slides having a first upwardly facing channel which receives the back rail of the shelf, each of the side rails

of the shelf resting on said support surface on the bracket at that side of the refrigerator, each of said slides having a forwardly projecting protrusion disposed below said first channel thereon, each slide being formed with an upwardly facing pocket and a second upwardly facing channel extending away from said pocket toward the inner side of the slide, and a pair of springs mounted respectively on the slides, each said spring having one end received in said pocket and having a segment extending across said second channel in the slide upwardly away from said one end of the spring, said segment of the spring being connected to an inverted loop portion disposed between an adjacent pair of said forwardly projecting rods on the shelf, said loop portion of the spring away from said one segment thereof bearing against the outer side edge of one of the rods in said pair, and said loop portion of the spring away from said one segment of the spring being connected to a downwardly projecting free end of the spring positioned at the inner side of the slide.

9. The combination of claim 8, wherein each of the slides has a channel which is open at the outer side of the slide and which receives the corresponding guide rail thereat, and each of said slides is adjustable along the corresponding horizontal arm carried by the shelf.

10. The combination of claim 8, wherein each of said brackets has an inwardly projecting protrusion which overlies the side rail of the shelf supported by that bracket to limit the upwardly displacement of the shelf thereat.

11. The combination of claim 8, wherein each guide rail carries a sleeve projecting rearward from the corresponding support bracket and positioned to be engaged by the slide on that guide rail to limit the forward movement of the slide.

12. The combination of claim 8, wherein each of the slides has a channel which is open at the outer side of the slide and which receives the corresponding guide rail

thereat, and each of said brackets has an inwardly projecting protrusion which overlies the side rail of the shelf supported by that bracket to limit the upward displacement of the shelf thereat.

- 5 13. A refrigerator shelf construction comprising a pair of rails disposed along the sides of the refrigerator in spaced relation thereto, bracket means for holding the front ends of said rails and formed above the rails to provide inwardly facing channels, the bottoms of which are in closely spaced relation to the sides of the refrigerator, a shelf having a pair of side and rear bars defining its lateral and back edges, said side bars being disposed in the channels of said bracket means outwardly of the rails, and means removably securing the rear of said shelf to said side rails including a block having an outwardly opening channel which receives the side rail and upwardly and downwardly opening channels which receives said back bars of said shelf, each outwardly opening channel having an open end at the outer side of the block which is larger than the respective rail for initially receiving said rail when the block is mounted thereon.

- 10 14. A device as described in claim 13, wherein said block is movable laterally on said back bars of the shelf and means is provided for releasably locking said block in a predetermined lateral position relative to said shelf.
